MIXING VALVE CONSTRUCTION

Richard Murray Lottes, St. Louis, Mo.

Application November 14, 1947, Serial No. 785,940

11 Claims. (Cl. 137—607)

1

The present invention relates generally to valve constructions, and more particularly to a valve construction incorporating two valves actuated by a single member for both simultaneous and independent action thereof.

An object of the present invention is to provide a novel valve construction in which two valves are operated by a single operating handle.

Another object is to provide a novel valve construction incorporating two rotatable valve elements which are readily and effectively individually or simultaneously rotated by a single operating member connected to the rotatable valve elements by a pair of links.

Another object is to provide a novel valve construction of the hot and cold fluid delivery type in which two valve elements are manipulated by a wobble stick type actuator and in which the connecting means between the actuator and valve elements is highly simplified, yet extremely efficient.

Another object is to provide a novel valve construction incorporating two rotatable valve elements and a wobble stick actuator in which a pair of slotted links of arcuate form are employed to transmit movement of the wobble stick to the valve elements for individual or simultaneous rotation thereof.

Another object is to provide a novel actuator and actuated elements construction incorporating a wobble stick actuator and a pair of links which is capable of wide application.

Other objects are to provide a novel valve construction which is compact, which is inexpensive to manufacture, which is readily formed and is of a simplified nature, which is employed by a user in obtaining hot or cold liquid or liquid at an in-between temperature through manipulation of a single actuator, which lends itself to esthetic application in bathrooms, kitchens, and the like, and which is designed for long service in conjunction with the usual type of washer now employed in similar construction.

Other objects and advantages are apparent from the following description taken with the accompanying drawings, in which:

Fig. 1 is a plan view of a valve construction formed in accordance with the teachings of the present invention;

Fig. 2 is a vertical longitudinal cross-sectional view on substantially the line 2—2 of Fig. 1, the actuator being shown in elevation except for a portion broken away to illustrate a structural detail;

Fig. 3 is a vertical transverse cross-sectional view on substantially the line 3—3 of Fig. 1, look-

2

ing forwardly in the direction of the arrows, the actuator being shown in elevation;

Fig. 4 is a vertical transverse cross-sectional view on substantially the line 4—4 of Fig. 1, looking rearwardly in the direction of the arrows, the actuator being shown in elevation and a portion of the housing being broken away to illustrate structural details;

Fig. 5 is a vertical cross-sectional view taken on substantially the line 5—5 of Fig. 1, the actuator being shown in elevation with the top portion broken away for conservation of space;

Fig. 6 is a vertical cross-sectional view on substantially the line 6—6 of Fig. 1, the actuator being shown in elevation and the top portion thereof being broken away for conservation of space;

Fig. 7 is a horizontal cross-sectional view on substantially the line 7—7 of Fig. 2;

Fig. 8 is a plan view of a valve element and associated connecting link;

Fig. 9 is a side elevational view thereof;

Figs. 10, 11, 12 and 13 are diagrammatic views of two valves, two connecting links, and the link engaging lower end of the actuator, illustrating the extreme movement positions of the several parts;

Fig. 14 is a plan view of a valve element and a modified connecting link; and

Fig. 15 is a diagrammatic view of two valves, two modified connecting links, and the connecting link engaging lower end of the actuator, this view being similar to Fig. 10.

Referring to the drawings more particularly by reference numerals, 20 indicates generally a valve construction incorporating the concepts of the present invention. Broadly, the valve construction 20 includes a housing 22, two rotatable valve elements 24 and 25 mounted in the housing, connecting links 27 and 28, an actuator 30, and a housing cover 32 which supports the actuator 30.

More specifically, the housing 22, in a preferred embodiment, includes a depending portion 35, which is divided into two inlet chambers 36 and 37 by a central partition wall 38. A threaded inlet opening 39 is provided in the outer wall of each chamber 36 and 37, which threadedly receive a hot water inlet pipe 40 and a cold water inlet pipe 41, by way of example (Fig. 4).

Above the depending portion 35 is an upper portion 45 which is formed to define a rear mixing chamber 46 and a forward liquid delivery spout 47. Depending from the upper portion 45 is an annular threaded skirt 49 by means of which the valve construction 20 is mounted in conjunction with a wash basin, or the like.

Angular partition webs 50 and 51 extend out-

wardly from the sides of the partition wall 38 near the upper edge thereof which separate the chambers 36 and 37, respectively, from the chamber 46 (Figs. 2, 5 and 6). Annular openings 52 and 53 are formed in the webs 50 and 51, respectively. At the rear of the mixing chamber 46 in a centrally located block 56 are two angularly directed threaded bores 54 and 55 which are concentric with and spaced from the apertures 52 and 53, respectively. The pitch of the threading of the bores 54 and 55 is large.

Rotatably disposed within the bores 54 and 55 are the threaded valve elements 24 and 25, respectively, which close the openings 52 and 53, respectively, in seated positions. The valve elements 24 and 25 are identical, except in having opposite threading and in the position of the head of a link mounting screw 57. Each rotatable valve element 24 and 25 includes a cylindrical body 58 (Fig. 9), a continuous thread 59, a washer 60 secured to the lower end by a suitable screw 61, and the screw 57 which threadedly engages the upper end of the cylindrical body 58 to secure thereto the respective links 27 and 28. For a purpose described below, a spacer washer 63 is disposed between the upper end of the rotatable valve element 25 and its associated connecting link 27.

The two links 27 and 28 are identical. Preferably, each is of the configuration clearly shown in Figs. 8 and 9 and includes an arcuate body portion 65 in which there are formed an elongated slot 66 and an aperture 67. Manifestly, the screw 57 of each valve element 24 and 25 extends through the aperture 67 to secure the links 27 and 28 to their respective valve elements. The links 27 and 28 are concentric to prevent clashing and blocking in the several movements thereof.

The cover 32 threadedly engages a threaded flange portion 70 of the upper portion 45 of the housing 22, and is formed with a central annular seat 71 of arcuate cross section surrounding an opening 72 extending through the cover 32. Outwardly of the seat 71 is a threaded annular wall 73. The portion 70 is large enough to permit installation or removal of a valve element 24 or 25 with its attached links 27 and 28, respectively.

The actuator 30 includes a ball 75 which rests on the seat 71. Extending diametrically from the ball 75 are stem portions 76 and 77, the former of which threadedly receives an actuating knob 78. The stem portion 76 and 77 may be an integral member or separate elements. The lower stem portion 77 extends through the elongated slots 66 in the links 27 and 28, the links 27 and 28 being concentric with the ball 75 in the drawings, a preferred though not required relation. A threaded plug 80 maintains the ball 75 in position on the seat 71, a suitable sealing washer 81 being provided to prevent leakage.

It is to be noted from Figs. 1, 5 and 6 that the valve elements 24 and 25 are radially disposed in respect to the ball 75 of the actuator 30, which is a preferred disposition.

In Figs. 14 and 15 are shown modified links 85 and 86, which are identical and which differ from the links 27 and 28 in that they are arcuate in plan as well as in elevation.

Operation

In Figs. 10 through 13, there is diagrammatically illustrated the operation of the present

novel valve construction 20. In Fig. 10, both valve elements 24 and 25 are closed, in which case the links 27 and 28 are engaged by the stem portion 77 in the positions shown. To open the valve element 25 without affecting the valve element 24, the stem portion 77 is moved along the slot 66 of the link 28 from its position of Fig. 10, which, as is clear from Fig. 11, rotates the link 27 clockwise to open the valve element 25. To open the valve element 24, the lower stem portion 77 is moved along the slot 66 of the link 27 from its position of Fig. 10, which, referring to Fig. 12, rotates the link 28 counterclockwise to open the valve element 24. To open both valve elements 24 and 25 an equal amount, the lower stem element 77 is moved inwardly towards the valve elements 24 and 25 from its position of Fig. 10 along a vertical center line drawn between the said valve elements, as is clear from Fig. 13. To open both valve elements 24 and 25, but to open one a greater degree than the other, it is but necessary to deviate the path of the lower stem element 77 to the right or to the left of the center line followed in opening both of said valve elements the same amount.

As is clear from the drawings, the link 28 is spaced from the link 27 when both valve elements 24 and 25 are in closed position by the washer 63. This is done in order to permit unseating rotation of the valve element 24 in its opening movement without clashing engagement with the link 27 when it is desired to open only the valve element 24.

The initial relationship of the lower stem portion 77 to the slots 66 of the links 27 and 28 is such as to allow a small clearance at the ends of the slots outwardly of the valve elements 24 and 25 when the valve elements 24 and 25 are in closed position (Fig. 10). Hence, as the washers 60 wear in the normal use of the valve construction 20, the portion 77 may be moved to the right (Fig. 10) to effect closing of the valve elements 24 and 25 to gradually utilize this provided clearance. The subsequent bodily movement of the valve elements 24 and 25 away from the lower stem portion 77 as the washers 60 wear only compensates slightly for such wear. Manifestly, were no clearance allowed as shown, the valve construction 20 would shortly become ineffective to close.

The actuator 30 is formed as a wobble stick member and, as is clear from the foregoing explanation and the drawings, has an outside modified triangular movement, since the lower stem portion 77 may move from its position of Fig. 10 along the slot 66 of link 28 to its position of Fig. 11, then substantially across to its position of Fig. 12, and thence back to its position of Fig. 10 along the slot 66 of the link 27. Interior movement is, of course, provided in order to effect a hot-cold fluid flow in the proportions desired.

The link construction shown in Figs. 14 and 15 functions the same in over-all operation as the link construction of Figs. 1 through 13. However, a greater degree of rotation may be obtained for the valve elements 24 and 25 by the links 85 and 86, since the advantage of the arcuate slots 88 thereof is utilized. This construction may be employed where pressure in a water system, or the like, is quite low and maximum opening of the valve elements is essential.

It is to be noted that the actuator 30 and the links 27 and 28 form a construction capable of wide use apart from the embodiment disclosed.

For example, a pair of rheostats or two motors could be controlled thereby.

It is manifest that there has been provided a valve construction which fulfills all of the objects and advantages sought therefor, and an actuator construction capable of wide application.

It is to be understood that the foregoing description and the accompanying drawings have been given by way of illustration and example. It is also to be understood that changes in form and utility of the elements, rearrangement of parts, and substitution of equivalent elements, which will be obvious to those skilled in the art, are contemplated as within the scope of the present invention which is limited only by the claims which follow.

What is claimed is:

1. Valve construction comprising, in combination, a pair of threaded rotatable valve elements controlling separate fluid passages, said elements being angularly disposed relative to each other so that their extended axes of rotation meet in a single point, an actuator mounted for universal pivotal movement about said single point for selectively moving said valve elements, supporting means for said elements and said actuator, and a link connected to each of said valve elements for movement therewith, both links being connected to said actuator for pivotal movement thereof by said actuator.

2. Valve construction comprising, in combination, a pair of threaded rotatable valve elements controlling separate fluid passages, said elements being angularly disposed relative to each other so that their extended axes of rotation meet in a single point, an actuator mounted for universal pivotal movement about said single point for selectively moving said valve elements, supporting means for said elements and said actuator, and a link connected to each of said valve elements for movement therewith, both links being connected to said actuator for selective individual and simultaneous pivotal movement thereof.

3. Valve construction comprising, in combination, a pair of movable valve elements controlling separate fluid passages, said elements being angularly disposed relative to each other so that their extended axes of movement meet in a single point, an actuator mounted for universal pivotal movement about said single point, supporting means for said elements and said actuator, a link connected to each of said valve elements for movement therewith, and means including a slideable connection between each of said links and the actuator for selective pivotal movement of said links upon movement of the actuator.

4. Valve construction comprising, in combination, a pair of valve elements controlling separate fluid passages, an actuator for selectively moving said valve elements of the wobble stick type including a center of movement, said valve elements being mounted for movement bodily radially of said center of movement of said actuator, means supporting said elements and said actuator in spaced relation for relative movement therebetween, and a link connected to each of said valve elements for movement therewith, both links including a longitudinal slot slidably receiving a portion of said actuator for pivotal movement thereof by said actuator, both links also being arcuate in form and disposed substantially concentric with said center of movement of said actuator.

5. Valve construction comprising, in combination, a pair of valve elements controlling separate

fluid passages, an actuator for selectively moving said valve elements of the wobble stick type including a center of movement, said valve elements being mounted for movement bodily radially of said center of movement of said actuator, means supporting said elements and said actuator in spaced relations for relative movement therebetween, and a link connected to each of said valve elements for movement therewith, both links including a longitudinal slot slidably receiving a portion of said actuator for pivotal movement thereof by said actuator, both links also being arcuate in form and disposed substantially concentric with said center of movement of said actuator, the longitudinal slots of both links being arcuate.

6. Valve construction comprising a housing including two separated fluid inlets, a closure valve element mounted in each inlet for helical rotation about angularly disposed individual axes, a single control member for said valve elements, said control member having extensions both inside and outside of the housing and a pair of identical links disposed within the housing directly connecting said valve elements and said control member for rotative movement of either or both valve elements by said control member, each of said links extending through a respective one of said individual axes and having a slideable connection with said control member.

7. Valve construction comprising a housing, a pair of valve elements mounted within the housing for individual rectilinear movement therein, a single actuator mounted in the housing for universal pivotal movement about a single pivot point therein, and individual link members disposed within the housing and interconnecting the respective valve elements with the actuator, said link members being in contiguous relation at their connection with the actuator.

8. Valve construction comprising a housing, a pair of valve elements mounted within the housing for individual rectilinear movement therein, a single actuator mounted in the housing for universal pivotal movement about a single pivot point therein, an elongated stem portion on the actuator disposed within the housing, and individual link members disposed within the housing and interconnecting the respective valve elements with said elongated stem portion, said link members being in contiguous relation at their connection with said stem portion.

9. Valve construction comprising a housing, a pair of valve elements mounted within the housing for individual rectilinear movement therein, a single actuator mounted in the housing for universal pivotal movement about a single pivot point therein, an elongated stem portion on the actuator disposed within the housing, and individual arcuate link members secured to the respective valve elements, said link members being disposed within the housing in concentricity with said pivot point and having respective juxtaposed connections with said stem portion.

10. Valve construction comprising a housing, a pair of valve elements mounted within the housing for individual rectilinear movement therein, a single actuator mounted in the housing for universal pivotal movement about a single pivot point therein, an elongated stem portion on the actuator disposed within the housing, and individual link members disposed within the housing in contiguous relation and secured to the respective valve elements, each of said link members having a slot engaged by said stem portion.

11. Valve construction comprising a housing, a pair of valve elements mounted within the housing for individual rectilinear movement therein, a single actuator mounted in the housing for universal pivotable movement about a single pivot point therein, an elongated stem portion on the actuator disposed within the housing, and individual link members disposed within the housing in contiguous relation and secured to the respective valve elements, each of said link members having an arcuate slot therein, each of said slots being slidably engaged by said stem portion.
